UNITED STATES PATENT OFFICE.

JONATHAN B. RICHARDSON, OF MOUNTAIN VIEW, CALIFORNIA.

CARTRIDGE-LOADING MACHINE.

SPECIFICATION forming part of Letters Patent No. 282,740, dated November 20, 1883.

Application filed May 17, 1883. (No model.)

To all whom it may concern:

Be it known that I, JONATHAN B. RICHARDSON, of Mountain View, county of Santa Clara, State of California, have invented an Improved Cartridge-Loading Machine; and I hereby declare the following to be a full, clear, and exact description thereof.

My invention relates to a new and useful cartridge-loading machine; and it consists in the means for receiving and supporting the shell, and in the means for charging it with powder, wads, and shot, which will hereinafter be fully explained.

The object of my invention is to provide a simple and effective machine for loading cartridges.

Referring to the accompanying drawings, Figure 1, Sheet 1, is a perspective view of my cartridge-loading machine, showing the powder-tube G lowered into a cartridge-shell, D. Fig. 2 is a side elevation, showing the powder-tube G raised out of the shell D. Fig. 3 is a front elevation.

A is the bed-plate, by which the machine is secured to the edge of a stand or table, B. To the forward edge of this is secured or formed a socket, a, from which a concave arm, b, extends downwardly. In this socket are secured spring arms or strips c, upon the projecting ends of which the shell D is fitted, and is held in place by a swinging arm, E, which is hinged to the concave arm b, and is held up under the shell by one of the hands of the operator. The arm b, being concave, serves as a guide or support for the shell when in place. From the top of socket a, on its outer side, extends a guide, d.

F is the wad-tube, supported from the bed-plate A by an arm, e. Its lower edge is held above the plate a sufficient distance to allow a wad to pass from under.

G is a tube, which serves the purpose both of a rammer and of a powder-conveyer. This tube is reciprocated vertically by means of the handle H. It is mounted in guides f, secured to the wad-tube, and is in a vertical line over the socket a, so that it may descend into the shell.

I is the powder-hopper secured upon top of the tube G.

J is the shot-hopper; having a neck, j, which

is connected with and opens into the socket a below its top, and between the open sides of the spring-strips.

To the powder-tube G, about midway, is secured the common cut-off device, consisting of the pivoted lever g, having upper and lower stop-plates, g' g'', respectively moving into and out of the tube through slits therein. The spring of this lever g holds the lower stop-plate normally within the tube, so that the powder rests upon it.

To the center of the lever g is secured a lug, h, which, when the tube G is forced down, comes in contact with a projecting arm, h', upon the wad-tube. This contact forces the lug h up, vibrates the lever g, withdraws its lower plate, g'', to allow the powder to run down, and throws in its upper plate to cut the powder off.

Pivoted to the top of one side of the wad-tube is the wad-arm K, the lower end, k, of which is turned at right angles and fits under the wad-tube. A spring, i, holds the end k normally under the wad-tube, with its edge against and on the same horizontal plane as the top of the socket a. The upper forward edge of the wad-arm K is formed as a cam or inclined plane, upon and against which a lug, l, secured to the powder-tube G travels. As the powder-tube descends, its lug l forces back the wad-arm K, and causes its lower end k to withdraw from under the wad-tube. A wad then falls down from said tube and rests upon the bed-plate A. When the powder-tube rises, the wad-arm is returned by its springs, and forces the wad over the socket in position under the powder-tube or rammer, when next it is forced down.

In the neck j of the shot-hopper is a cut-off device similar to that shown on the powder-tube. It consists of the vibrating spring-lever m, having stop-plates m' m'', working through slits in the neck. With the lower end of lever m is connected a chain or cord, n, the upper end of which is secured to the handle H.

The operation of my machine is as follows: The shell is fitted under the socket a upon the spring-strips c, which serve to hold it. The left hand grasps the swinging arm E, and presses it tightly up against the bottom of the shell, in order to resist the thrust of the ram-

mer in loading, Fig. 1. The right hand grasps the handle H, and forces down the powder-tube, which descends through the socket a and enters the shell. When the lug h comes in contact with the arm h', the charge of powder runs down through the tube G into the shell. As the tube descends, the wad-arm K is forced back by the lug l, and a wad lies on the plate A. Then the tube G is raised, and when it reaches a point above socket a the wad-arm, being released from the lug l, is returned by its spring i, to force the wad over the socket a. The tube G, now serving as a rammer, is again forced down, and drives the wad home; but on account of the charge of powder and the wad being in the shell, the tube cannot descend far enough this time to cause the engagement of its cut-off mechanism with the arm h', thus avoiding a fresh charge of powder. Now, as it is customary to place two wads over the powder, I again raise the tube G, and upon the downstroke drive a second wad home. This is the advantage in this machine. As the succeeding steps do not take place until the shell is fully prepared to receive their operations, I may, by reciprocating the tube G, drive down one, two, or more wads, as I may desire. Then the tube is raised high enough to draw on the chain n, which raises the lever m and allows the charge of shot to pass into the shell. The tube in being thus raised will of course allow another wad to be forced to position over the socket a; but as the neck of the shot-hopper enters below the top of the socket the shot-charge passes in without interfering with said wad. The downward movement of the tube G forces this wad to its place on the shot, and then, by releasing the supporting-arm E, the loaded cartridge is forced off its spring-holder. The machine is simple in construction and effective in operation, being at the same time light enough to be readily transportable.

Having thus described my invention, what I claim as new, and desire to secure by Letters Patent, is—

1. In a cartridge-loading machine, the bed-plate A, having a socket, a, and an arm, b, in combination with the spring-holder c, for receiving the shell, and the swinging arm E, for supporting it and resisting the thrust in the loading process, substantially as herein described.

2. In a cartridge-loading machine, the bed-plate A, having secured thereto a means for holding and supporting the shell, in combination with the reciprocating powder-tube and rammer G, the lower end of which enters the shell, and a means for automatically releasing a charge of powder from said tube when in the shell, substantially as herein described.

3. In a cartridge-loading machine, the bed-plate A, and a means for holding and supporting the shell, in combination with the reciprocating powder-tube and rammer G, and

the means for releasing the charge of powder, 65 consisting of the vibrating lever g, having stop-plates g' g'', and provided with a lug, h, projecting at right angles from its rear, and the arm h', adapted to be struck by the lug h, substantially as herein described. 70

4. In a cartridge-loading machine, the bed-plate A, having socket a, the spring-holder c, and swinging arm E, for receiving and supporting the shell, in combination with the reciprocating powder-tube and rammer G, having powder-hopper I on its top, and handle H, and the means for releasing its charge of powder, consisting of the vibrating lever g, having stop-plates g' g'', and provided with lug h, projecting at right angles from its rear, 75 and the arm h', adapted to be struck by the lug h, substantially as herein described. 80

5. In a cartridge-loading machine, the bed-plate A, having a means for receiving and supporting the shell, in combination with the reciprocating powder-tube and rammer G, having a means for automatically discharging a powder-charge into the shell, and the wad-tube F, supported from and raised above the bed-plate, the pivoted spring-arm K, having a cam or inclined edge and end, k, forcing a wad from under the wad-tube to a position over the shell, and drawn back by a lug, l, on the reciprocating tube G, traveling against the cam-edge of the arm K, substantially as 95 herein described.

6. In a cartridge-loading machine, the bed-plate A, having socket a, spring-holder c, and a means for supporting the shell, in combination with the reciprocating powder-tube and rammer G, having a lug, l, and a means for discharging a powder-charge within the shell, consisting of the vibrating lever g and stop-plates g' g'', and provided with the lug h, projecting at right angles from its rear, and arm h', adapted to be struck by the lug h, the wad-tube F, and the swinging pivoted wad-arm K, having end k, and operated by a spring, i, to force the wad over the socket a, and by the lug l on the powder-tube to withdraw its end from under the wad-tube, substantially as herein described. 100 105 110

7. In a cartridge-loading machine, the bed-plate A, having socket a, and a means for holding the shell thereunder, in combination with the shot-hopper J, having a neck, j, entering the socket a, the reciprocating powder-tube and rammer G, and the means for releasing the charge of shot, consisting of the vibrating lever m, stop-plates m' m'', and chain n, connected with the lever m, and with the reciprocating powder-tube G, substantially as herein described. 115 120

In witness whereof I hereunto set my hand.
JONATHAN B. RICHARDSON.
